UNITED STATES PATENT OFFICE.

JAMES H. GOOCH, OF PARIS, TEXAS.

BURNER.

Application filed September 26, 1922. Serial No. 539,392.

To all whom it may concern:

Be it known that I, JAMES H. GOOCH, a citizen of the United States, residing at Paris, in the county of Lamar and State of Texas, have invented certain new and useful Improvements in Burners, of which the following is a specification, reference being had to the accompanying drawings.

The present invention has for its purpose the provision of a device of this kind adapted for use in connection with stoves, ranges and furnaces, and constructed for burning low grade oils.

Another purpose is to provide a device of this character, wherein the burner includes a burner pan, which projects through the feed door opening, in combination with a burner gate resting upon the sides of the burner pan, and between the lower curvature of which and the bottom of the burner pan air is drawn into the burner pan, as the low grade oil is fed into and upon the latter, so that the air may volatilize or vaporize the oil, and thereby provide a proper combustion of the fuel for burning. Products of combustion sweep or travel upwardly over the front face of the oven, and over the top, and pass out through the flue of the stove or range, thereby thoroughly heating the oven and the top of the stove or range, for baking and cooking.

Still another purpose is the provision of a burner of this character, wherein the oil when being fed into and upon the burner pan produces a partial injector action, to draw the air into the burner chamber, so it may sweep across the surface of the oil, to volatilize and vaporize the oil.

Heretofore burners are arranged in the stove or range over the top, or in such a manner that the burner cannot be adjusted or removed while the burner is hot, whereas in the present invention it is the aim to provide a burner which is inserted through the feed door opening from the front of the stove, so that it may be easily removed, while the same is hot. In other words the feed door opening includes a supporting frame, to which a frame of the burner plate proper is bolted, access being had to the bolts from the exterior, by means of a screw-driver wrench, and when the nuts on the bolts have been detached, the burner plate can be easily removed from the exterior.

A still further purpose is the provision of a burner, wherein the sides of the burner

pan have curved recesses for the reception of the curved under surface of a curved deflector at the bottom of the burner gate, for detachably supporting the burner gate in its proper position, so that it can be easily removed at any time for the purpose of cleaning out the burner pan. The curvature of the deflector at the base of the burner gate constitutes means for facilitating the passage of air over the surface of the oil.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and claimed.

In the drawings:—

Figure 1 is a sectional view through a conventional form of cook stove or range, showing the application of the burner constructed in accordance with the invention;

Figure 2 is a view in front elevation of the cook stove or range, likewise showing the burner applied;

Figure 3 is a plan view of the burner on line 3—3 of Figure 1;

Figure 4 is a detail perspective view of one side of the burner pan, showing one of the recesses for a burner gate;

Figure 5 is a detail perspective view of the burner gate.

Referring to the drawings, 1 designates a conventional form of cook stove or range, which has a feed door opening 2. Bolted to the inner surface of the margin of the feed door opening 2 is a metal frame 3, through the opening of which a burner proper extends. The bolts 4 which secure the frame 3 in place are passed through the frame and through the margin of the feed door opening from the interior, so that the nuts appear upon the exterior of the stove or range.

The burner, which is designated by the numeral 6, comprises a burner pan 7 having a bottom 8, sides 9, and an outer end curved wall 10. The wall 10 merges arcuately into the bottom and the inner end of the bottom terminates in an end piece 11. This end piece 11 causes to be formed an inner flange, substantially half as high as the

sides of the burner pan, which acts to deflect the products of combustion upwardly through the combustion chamber of the stove. The flange also prevents the oil from flowing over the inner end of the burner pan. Rising from and secured to the sides 9 of the burner pan are uprights 12. In fact the uprights 12 constitute integral parts of the sides of the burner pan, and are also bolted at 13 to the margin of the opening of the frame 3. The bolts 13 pass through the frame and through the uprights from the interior of the stove or range, and have their nuts applied thereto from the exterior. Obviously such nuts may be easily removed from the exterior, and in such an instance the burner may be withdrawn from the opening of the frame, and hence removed from the interior of the range. The uprights 12 are reinforced relatively to the sides of the burner pan by means of the braces 14, which form integral parts of the uprights and the sides of the pan.

The opposite sides of the burner pan adjacent the uprights and the braces 14 have arcuate recesses 15, and in order to close the opening between the uprights, in fact the opening formed through the frame 3 a burner gate or hood 16 is provided. The opposite vertical edges of the gate or hood engage between the uprights 12, as shown in the plan view, and also have flanges 17 overlying the uprights, to prevent the burner gate from tilting inwardly, as well as preventing the same from tilting outwardly. The exterior surface of the burner gate has a suitable handle 18, which constitutes an integral part of the gate, and by which the gate may be easily removed and reinserted, whenever the occasion requires.

The lower portion of the gate terminates in an arcuate wall 19, the curvature of which corresponds to the recesses 15, so that the arcuate wall may engage said recesses and thereby support the gate in a vertical position, filling up the space between the uprights and closing the opening in the frame 3, except that portion below the arcuate wall 19. The arcuate wall 19 is so curved and spaced from the bottom of the burner pan as to act as a deflector, and since the low grade or other character of oil enters the burner pan through its forward curved wall an injector action is created below the curved wall 19, hence causing the air to enter the burner pan below said wall 19, whereby the air may sweep across the surface of the oil to volatilize the oil and mix with the vapor arising from the oil, thereby creating a combustible gas or vapor, which may be consumed in the combustion chamber of the stove or range. In using the burner, a small quantity of oil is allowed to enter the burner pan, which oil is then lighted, in which case

the flame arising from the ignited oil will 65 pass upwardly over the front face of the oven, and over the top thereof to thoroughly heat the same for baking and cooking, the heat from the flame also heating the top of the stove. The flame passing from the surface of the oil acts to create a suction in the passage below the arcuate wall 19.

The forward arcuate wall 10 of the burner pan has a boss 20, through which and through the wall an opening 21 is formed. This opening receives a suitable oil supply pipe 22. This supply pipe 22 may receive oil from any suitable source (not shown), and includes a vertical portion 23 which has a valve 24, for governing the supply of oil to 80 enter the burner pan.

It will be noted that the curvature of the recesses 15 constitute means for holding the burner gate upright and the vertical flanges 17 against the side margins of the frame 3, so that the lower wall 19 of the burner gate will properly direct the products of combustion upwardly and rearwardly through the range.

The invention having been set forth, what 90 is claimed is:—

1. In combination with a stove provided in its front with a feed opening, a pan disposed horizontally within said feed opening and projecting beyond the front of the stove, said pan having front and side flanges, a fuel feed pipe leading through said front flange and discharging into the pan, uprights rising from the sides of the pan, said side flanges being formed with curved recesses 95 adjacent said uprights, and a gate fitting between said uprights and having its lower end formed with a curved plate portion seating within said recesses.

2. A burner for a stove having a feed 105 opening in its front, comprising a horizontally disposed pan located at the bottom of said opening and projecting beyond the front of the stove, said pan having a rear deflector wall, side walls and a curved front 110 wall, uprights formed integrally upon the sides of the pan, the side flanges being formed with curved recesses extending downwardly from the upper edges, a feed pipe leading through said curved front wall and discharging onto the pan, and a removable gate fitting between said uprights and formed at its lower edge with a curved wall portion seating within said recesses, said gate having lateral flanges bearing against 120 the outer faces of the uprights to prevent tilting, the curved wall portion of the gate and the curved front wall of the pan cooperating to define an air inlet passage.

In testimony whereof I hereunto affix my 125 signature.

JAMES H. GOOCH.
